UNITED STATES PATENT OFFICE

105,085

DESIGN FOR AN AIRPLANE

Berthoud C. Boulton, Towson, and William W. Symington, Jr., Baltimore, Md., assignors to The Glenn L. Martin Company, Baltimore, Md.

Application October 9, 1935, Serial No. 58,919

Term of patent 14 years

To all whom it may concern:

Be it known that we, Berthoud C. Boulton and William W. Symington, Jr., citizens of the United States and residents, respectively, of Towson, in the county of Baltimore and State of Maryland, and of Baltimore in the State of Maryland, have invented a new, original, and ornamental Design for an Airplane, of which the following is a specification, reference being had to the accompanying drawings, forming part thereof.

Fig. 1 is a perspective view of the subject airplane in flight;

Fig. 2 is a perspective view differing from Figure 1 in angularity as well as in showing retractable wheels and auxiliary wing surfaces while extended either for taking off or landing;

Fig. 3 is a front elevation of the airplane depicted by Figure 2;

Fig. 4 is a side elevation of Figure 3; and

Fig. 5 is a side elevation of the airplane depicted by Figure 1.

The subject design comprises the ornamental configuration as viewed in its entirety including as principal features the relation of the gunner's turret contour in collaboration with the unbroken alignment of the two cockpit enclosures with the tail surfaces together with the relation of the outlines of the fuselage to the contour of the tapered main wings including the pedestal type landing wheels and the rearwardly extended auxiliary wing surfaces.

We claim:

The ornamental design for an airplane substantially as shown and described.

BERTHOUD C. BOULTON.
WILLIAM W. SYMINGTON, JR.
